UNITED STATES PATENT OFFICE.

LEO D. JONES, OF PHILADELPHIA, PENNSYLVANIA, ASSIGNOR TO THE SHARPLES SPECIALTY COMPANY, OF PHILADELPHIA, PENNSYLVANIA, A CORPORATION OF DELAWARE.

METHOD AND MECHANISM FOR REMOVING CENTRIFUGE EFFLUENTS.

Original application filed October 7, 1921, Serial No. 506,165. Divided and this application filed April 9, 1927. Serial No. 182,236.

The method and mechanism of this invention are designed to facilitate the removal of viscous or other effluents discharged from centrifugal rotors and disposed to adhere to receivers therefor, thus accumulating and interfering with the desired operations.

The invention is characterized by the discharge of a fluid within the receptacle into which an effluent from a centrifugal rotor is received and so affecting said effluent as to prevent its accumulating in the receptacle.

In the treatment of petroleum oil for the separation therefrom of petrolatum or wax contained therein, the oil has been chilled and then run through a centrifugal rotor from which the separated wax and wax freed oil are delivered to receiving compartments or "covers"; a carrier liquid, such as brine, being used in the rotor for facilitating the operation.

As the wax discharged from the bowl is viscous, it is disposed to adhere to the walls of the compartment or "cover" into which it is discharged and to accumulate, with resulting obstruction of the operation after some time.

In the preferred practice of my invention, hot brine is delivered against the top of the compartment for receiving the wax effluent and washes such top so as to heat the same and remove the wax therefrom, the wax being heated by the heated surface against which it is thrown, by contact with the brine and by the heated atmosphere of the compartment, so that its fluidity is increased and its discharge from the "cover" or receptacle is facilitated.

The invention is comprised in the construction and operation set out in the following description and the accompanying drawings in illustration thereof.

In the drawings, Fig. 1 is a broken sectional view showing the top of a centrifugal rotor provided with improvements of my invention, and Fig. 2 is a part sectional plan of the construction as seen with the top cover removed.

In the drawings, the centrifugal rotor 1 has the neck 2, by which it is suspended and revolved, and is provided with the passages 3 and 4, through which the centrifu-

gally separated and stratified constituents are discharged.

In the separation of wax from chilled oil, 55 the separated wax flows through the passages 3 to the channel 5 whence it is discharged over the weir or dam 6 concentric with the rotor, and the wax freed oil flows to the discharge passages 4 over the weir or 60 dam 7 and through the compartment 8 concentric with the rotor.

A "cover" 9, supported detachably by the case 10, provides the compartment 11 into which the wax is discharged as it is delivered over the weir 6, and a "cover" 12, supported detachably by the "cover" 9, provides a compartment 13 for receiving the wax freed oil from the passage or passages 4.

A tubular ring or delivery conduit 14, 70 connected with a supply conduit 15 and provided with the apertures 14', encircles the bowl neck 2 in proximity to the top of the bottom surface of the conical bottom 12' of the cover 12, the part 12' forming the top 75 of the compartment 11. The conduit 14 is adapted for discharging hot fluid through its peripheral openings 14' against the bottom surface of the part 12' above the wax discharged over the weir 6, such wax in greater or less amount being thrown against the part 12'. As the heating fluid or hot brine, which is fed through the conduit 15 to the conduit 14 and discharged through the openings 14' thereof, washes the bottom surface of the part 12', heats the compartment 11, heats the wax and acts directly upon the wax, the latter is thus caused to flow freely from the compartment 11 through the spout 11' thereof.

From the foregoing it will be apparent that hot fluid projected against the common wall dividing compartment 11 from compartment 13 will heat that common wall 12', and also the atmosphere within compartment 95 11, and the heat of that common wall 12' will heat the atmosphere in compartments 11 and 13.

This application constitutes a division of my copending application Ser. No. 506,165, filed October 7, 1921, in which the broad aspect of my invention is claimed wherein the condition of a substance discharged in dispersed form from a centrifugal machine

in which the substance was subjected to centrifugal treatment, is controlled by regulating the condition of the atmosphere within which the substance is so discharged; the 5 claims of said application also covering that species of my invention wherein the condition of the substance so discharged is controlled by regulating the temperature of the atmosphere within which the substance exists 10 in dispersed state.

What I claim as new and desire to secure by Letters Patent of the United States is:

1. The method of separating wax from petroleum which comprises chilling the wax bearing oil to such temperature as will precipitate the wax, centrifugally separating the wax from petroleum and separately discharging the wax and wax-feed oil from the influence of centrifugal force, and discharging 20 a hot fluid into contact with the wax after it leaves the influence of centrifugal force to facilitate removal thereafter of said wax.

2. The method of separating wax from petroleum which comprises chilling the wax bearing oil to such temperature as will precipitate the wax, centrifugally separating the wax from the oil and discharging the separated wax from the influence of centrifugal force against the wall of a collecting receptacle while discharging a jet of hot fluid against said wall and thereby heating the wax to facilitate further removal of the wax.

3. The method of separating wax from petroleum which comprises chilling the wax bearing oil to such temperature as will precipitate the wax, centrifugally separating the wax from the oil and separately discharging the separated wax against a partition while projecting hot fluid against the surface of the partition impinged by the wax and flowing the wax-free oil over the opposite surface of said partition.

4. In centrifugal apparatus for the separation of wax from petroleum of a centrifugal bowl having outlets respectively for the discharge of wax and wax-free oil, receptacles respectively positioned to receive oil and wax discharged from said outlets, and means heating the interior of the oil receiving receptacle.

5. In centrifugal apparatus for the separation of wax from petroleum, the combination of a centrifugal bowl having outlets respectively for the discharge of wax and wax-free oil, receptacles provided with spouts and respectively positioned to re-

ceive oil and wax discharged from said outlets, and means heating the interior of the oil receiving receptacle and the wax and washing wax toward the spout of its receptacle.

6. The method which consists in centrifugally separating wax from petroleum oil, 60 separately discharging the separated wax and wax freed oil, and bringing brine at a temperature to melt the wax into contact with the discharging wax.

7. The process of separating wax from petroleum oil, which comprises reducing the oil containing wax in solution to a temperature sufficiently low to throw the wax out of solution, separating the wax from the oil by centrifugal force, separately discharging the 75 separated wax and oil out of the influence of the centrifugal force and subjecting the separated wax as it is so discharged and passed from the influence of centrifugal force to heat to render it more free flowing, 80 and then flowing away the heated wax.

8. The process of separating wax from petroleum oil, which comprises reducing the solution to a temperature sufficiently low to throw the wax out of solution, separating 85 the wax from the oil by centrifugal force, subjecting the discharging separating wax to heat to render it more free flowing, and flowing away the heated wax.

9. The method of separating wax from petroleum which comprises chilling the wax-bearing oil to such temperature as will precipitate the wax, centrifugally separating the wax from the oil and separately discharging the wax and wax-free oil from 95 the influence of centrifugal force, and discharging hot liquid into contact with the separated wax as it is so discharged and passed from the influence of centrifugal force to heat the wax and thereby heating 100 the wax to render it more free flowing and washing the wax away.

10. The method of separating wax from petroleum which comprises chilling the wax-bearing oil to such temperature as will 105 precipitate the wax, centrifugally separating the wax from the oil and separately discharging the wax against the wall of a collecting receptacle, and discharging liquid against said wall and thereby washing the 110 discharged wax toward an outlet of said receptacle.

In testimony whereof, I have signed my name to this specification.

LEO D. JONES.
